UNITED STATES PATENT OFFICE.

BERNARD E. FERNOW, JR., OF MILWAUKEE, WISCONSIN, ASSIGNOR, BY MESNE ASSIGNMENTS, TO THE CUTLER-HAMMER MFG. CO., OF MILWAUKEE, WISCONSIN, A CORPORATION OF WISCONSIN.

ELECTROMAGNETIC CLUTCH.

1,325,011.

Specification of Letters Patent. Patented Dec. 16, 1919.

Application filed June 5, 1916. Serial No. 101,823.

To all whom it may concern:

Be it known that I, BERNARD E. FERNOW, Jr., a citizen of the United States, residing at Milwaukee, in the county of Milwaukee, 5 and State of Wisconsin, have invented new and useful Improvements in Electromagnetic Clutches, of which the following is a full, clear, concise, and exact description, reference being had to the accompanying drawing, forming a part of this specification.

This invention relates to electromagnetic clutches and more particularly to those of the annular type.

15 Among the objects of the invention is to provide a clutch of the type stated which may be readily assembled upon a line shaft without displacement of the latter.

20 A further object is to facilitate renewal or replacement of the various clutch parts.

Other objects will appear as the description proceeds.

Referring to the drawing, wherein is illustrated an embodiment of the invention, 25 Figure 1 is an edge view, partly in section, of a clutch constructed in accordance therewith, while

Fig. 2 is a side view of the same.

The clutch comprises an annular field 30 member 1 and an annular armature member 2, the former being adapted to be fixed to a driving shaft and the latter being fixed to a driven gear through the medium of a spring disk.

35 The field member comprises an annular casing 3 having an extended hub 4 to fit a driving shaft and said casing including the hub slit diametrically on line 5 and the sections thereof are adapted to be secured together by bolts 6 passing through suitable lugs 7 provided thereon. An annular channel 8 is formed near the periphery of the casing 3 in which is housed the electromagnetic element which comprises a plurality of 40 (in the present case ten) separate electromagnets 9 equally spaced.

Each of the said electromagnets comprises a core 10 fixed within the channel 8 by means of a screw bolt 11 extending through 45 the wall of the casing, the core 10 being surrounded by a winding 12.

The surrounding space within the channel 8 is filled with a suitable impregnating compound while the exterior of the channel 50 is closed by an annular coil shield 13. The

shield is formed with openings 14 through which the outer ends of the cores 10 project and is split in sections coinciding with those of the casing 3. The electromagnets carried by each section of the casing are 60 adapted to be connected in series by connection of adjacent terminals thereof and the electromagnets of the two sections are adapted to be series connected by a conducting strip 15 serving to bridge terminals 16 65 one being provided on each section of the field member.

Current is supplied to the above described electromagnetic element from a split collector ring 17 which is flanged upon hub 4 70 of the casing 3 for rotation therewith. Referring to Fig. 2, the circuit of the electromagnets may be traced as follows, from the collector ring 17 by means of terminals 18 and conductor 19 to casing terminal 20, 75 thence through the windings of the electromagnets mounted within the left half of the casing 3 to terminal 16, through the conductive strip 15 to terminal 16 on the right half of the casing and returning to the right 80 ring terminal 18 by a course similar to that above described.

A split friction ring 21 having a suitable lining 22 is bolted upon the engaging face of the field member 1 radially outside the channel 8, the lining 22 being positioned for frictional contact with the armature plate 2 when the clutch is engaged.

The armature plate 2 and gear 23 are both split diametrically along a common line, the 90 respective sections thereof being clamped together by means of bolts 24 and 25 passed through appropriate lugs 26 and 27. The flexible disk 28 is also split diametrically but preferably on a plane at right angles to 95 that of the armature plate 2.

The disk 28 is attached to plate 2 near its periphery by means of bolts 29, while the lugs 26 on said plate projects through suitable openings 30 in said disk whereby said lugs and the bolts carried thereby are rendered easily accessible. Said disk is furthermore attached to the gear 23 by means of the centrally located screw bolts 31, whereby said disk constitutes a resilient support for 105 the armature plates biasing the same away from the field member.

A spacing washer 32 which is attached to the casing 3 and closely surrounds the shaft opening therein serves to maintain the gear 110

23 and its attached parts normally spaced an appreciable distance from said casing.

Upon energization of the various electromagnets the armature plate 2 is drawn into 5 frictional engagement with the engaging surface 22 of the field member in a manner well understood. By the above described action the resilient disk 28 is placed under tension, whereby upon deenergization of the 10 electromagnets said disk acts to disengage the armature plate 2 from said friction surface. The magnet cores 10 are of such length as to clear the plate 2 at all times.

From the above description it is apparent 15 that the clutch parts may be readily mounted in any desired position upon or removed from a fixed shaft without disconnecting the latter and without shifting the assembled clutch axially thereof. Moreover, 20 the construction of the magnetic element in the form of a plurality of separate magnets permits separation of the field member into halves as described while facilitating repair or renewal of the various units of said magnetic element without disadjustment of un- 25 attached parts.

What I claim as new and desire to secure by Letters Patent is:

1. An electromagnetic clutch element, comprising an annular field member diametrically split to provide separable sections for assembly about a shaft, each of said sections being integrally formed and including a hub portion and a channeled portion located circumferentially thereof, a plurality of electromagnetic windings inclosed within said channeled portion, the latter serving as a common magnetic frame for the former, said sections having means for securing the 40 same in assembled relation.

2. An electromagnetic clutch element, comprising an annular field member diametrically split to provide separable sections for assembly about a shaft, each of said sections being integrally formed and including a hub portion and a channeled portion located circumferentially thereof, a plurality of electromagnetic windings inclosed within said channeled portion, the latter serving as a common magnetic frame for the former, said sections having means for securing the same in assembled relation comprising sets of registering lugs located peripherally of said hub portions and of said channeled portions 55 and bolts passing through said lugs.

3. In an electromagnetic clutch, in combination, an annular field member comprising a centrally located hub, a peripheral flange formed integral therewith and an intermediate channeled portion, a plurality of electromagnetic windings inclosed within said channeled portion, the latter constituting a common magnetic support for the former, a friction ring secured to said flange, 60 said field member being diametrically split

in a plane passing between said windings to provide similar sections for assembly about a shaft, means for securing said sections in assembled relation, and an armature member adapted for driving engagement with 70 said friction ring.

4. An electromagnetic clutch element comprising, in combination, an annular field member including a centrally located hub, a peripheral flange formed integral therewith and an intermediate channeled portion, a plurality of electromagnetic windings inclosed within said channeled portion, the latter constituting a common magnetic support for the former, and a friction ring secured 80 to said flange, said field member being diametrically split in a plane passing between said windings to provide similar sections for assembly about a shaft, said sections having means for securing the same together comprising sets of registering lugs located peripherally of said hub portions and of said channeled portions and bolts passing through said lugs. 85

5. An electromagnetic clutch armature comprising, in combination, an annular magnetic member and a resilient disk peripherally secured to said member for supporting the same, said member and said disk being diametrically split to provide separable sections for assembly about a shaft and having means for securing the same in assembled relation.

6. An electromagnetic clutch armature comprising, in combination, an annular 100 magnetic member and a resilient annular disk peripherally secured to said magnetic member for supporting the same, said member and said disk being split along diametrical planes at right angles to each other for 105 permitting assembly thereof about a shaft and having means for securing the same in assembled relation.

7. An electromagnetic clutch armature comprising, in combination, an annular 110 magnetic member and a resilient annular disk peripherally secured to said member for supporting the same, said member and said disk being diametrically split to permit assembly thereof about a shaft, the sections of 115 said magnetic member having registering pairs of axially extending lugs for securing the same together and said disk being provided with correspondingly located openings to permit passage of said lugs therethrough 120 for accessibility of the latter.

8. In an electromagnetic clutch, in combination, an annular field member comprising a centrally located hub, a peripheral flange formed integral therewith and an intermediate channeled portion, a plurality of electromagnetic windings inclosed within said channeled portion, the latter constituting a common magnetic support for the former, a friction ring secured to said flange, 125 said field member being diametrically split

member being diametrically split in a plane passing between said windings to provide similar sections for assembly about a shaft, means for securing said sections in assembled relation, an armature for driving engagement with said friction ring, said armature comprising an annular magnetic mem-

ber and a resilient annular support peripherally secured thereto, said member and said support being diametrically split for permitting assembly thereof about a shaft.

In witness whereof, I have hereunto subscribed my name.

BERNARD E. FERNOW, Jr.
